(57) **CLAIM**

The ornamental design for a massager, as shown and described.

DESCRIPTION

FIG. 1 is a front perspective view of a massager showing our new design;

FIG. 2 is a rear perspective view thereof;

FIG. 3 is another perspective view thereof shown in a condition of use;

FIG. 4 is a front elevation view thereof;

FIG. 5 is a rear elevation view thereof;

FIG. 6 is a right elevation view thereof;

FIG. 7 is a left elevation view thereof;

FIG. 8 is a top plan view thereof; and,

FIG. 9 is a bottom plan view thereof.

The broken lines in the drawings are for the purposes of illustrating portions of the massager, which form no part of the claimed design. The figure shown in broken lines in FIG. 3 is for the purpose of illustrating environmental structure, which forms no part of the claimed design.

1 Claim, 8 Drawing Sheets
